EYE-SCREW DRIVING TOOL

Roland L. Quirion, Waterville, Maine

Application November 8, 1946, Serial No. 708,709

2 Claims. (Cl. 145—50)

1

The present invention relates to what is believed to be a novel and practical multiple purpose tool which is expressly, but not necessarily, adapted for use in inserting, screwing and unscrewing so-called screw-eyes.

It is a matter of common knowledge that all sorts of make shift instruments and devices have been employed by persons handling, applying and removing so-called screw-eyes. Claw hammers, screw-drivers and instruments such as may be handy at the time, are used in various ways in driving and removing screw-eyes. Confronted with such conditions, I have found it expedient and practicable to devise a tool which is particularly made up and especially designed to better accomplish the ends sought.

An object of the invention is to provide a simple, expedient and economical tool which lends itself admirably well to accomplish the results desired, said tool having an especially constructed adaptor which conforms nicely to the stock shape of the eye into which it is inserted and lodged, appropriate handle means being provided to facilitate the use of said adaptor.

More specifically, in carrying out the preferred embodiment of the invention, I provide a simple hand-crank, one limb of which is fashioned into a hole forming awl and the other end of which is formed into the aforementioned adaptor, the latter being in the nature of a lateral undulated foot.

Other objects, features and advantages will become more readily apparent from the following description and the accompanying illustrative drawings.

In the drawings, wherein like numerals are employed to designate like parts throughout the views:

Figure 1 is an elevational view of a tool constructed in accordance with the principles of the present invention;

Figure 2 is a view at right angles to Figure 1 observing same in a direction from right to left and showing the manner in which the adaptor is connected with the eye of a screw-eye to drive and screw same into place; and,

Figure 3 is a view like Figure 2, but showing the manner in which the same tool is employed to unscrew said screw-eye.

Referring now to the drawings by distinguishing reference numerals, it will be seen that the hand-crank, as a unitary device, is denoted by the numeral 5, the same comprising limbs 6 and 7 at approximate right angles to each other. The principal limb 7 is in effect a lever providing

the desired leverage for both screwing and unscrewing the screw-eye 8. The limb 6 is primarily a handle and is provided at longitudinally spaced points with retaining washers 9 and 10 for a swivelly mounted hand-grip 11. The right-hand end portion of the limb 6 is shouldered as at 12 and then tapered and ribbed to provide a triple-rib awl 13. This awl is used, obviously, to pierce the surface of a piece of wood and to pilot a hole into same for purposes of getting the screw-eye started, this in an obvious manner. The adaptor on the free end of the lever forming limb 7 is denoted, generally speaking, by the numeral 14 and is in the form of a lateral foot. The foot is of undulated form and is characterized essentially by a heel portion 15 and a terminal toe portion 16. The undulated formation of the foot is such as to define a crotch or seat 17 at the juncture of the limb 10 and foot and the intermediate bend defines a similar crotch or seat 18 in the longitudinal arch portion of the foot. The tip of the toe 16 is hooked as shown and this defines a third crotch or seat 19. The undulated formation of the foot serves to provide the desired seating, abutment, and end thrust facilities brought out in the two positions as shown in Figure 2. In Figure 2, a portion of the eye is accommodated in the outer crotch or seat 19 and a diametrically opposite portion of the eye is accommodated in the crotch or seat 18. In Figure 3, we see the crotch or seat 17 coming into play and the crest portion of the toe 16 functioning as an end thrust abutment. It follows, that the undulated foot has a double purpose formation whereby it may be conveniently used (see Figure 2) for screwing an eye-screw home, so to speak; whereas, in Figure 3 it is employed to unscrew or remove the screw-eye.

The hand-grip on the limb 6 serves to conveniently handle the tool and facilitates affording the user effectively usable leverage to accomplish what is wanted with ease and satisfaction. The hand-grip may also come in handy in punching the awl into a wood surface to pilot a hole for purposes of starting a screw. It has also been found that the hand-grip 11 may be held and the part 7 may be used somewhat as a handle to facilitate "boring" a hole in hard-wood by way of the awl. In other words, the pointed end of the awl is placed against the hard-wood surface and where it cannot be punched in freely, the hand-grip is held securely to function as a bearing and then the limb 6 is oscillated

or rocked back and forth through the medium of the limb 7, using the latter as a handle, whereby to "drill" an opening into the work.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. A multiple purpose tool expressly adapted to facilitate steps of applying and removing eye screws comprising a rigid one-piece crank embodying complementary rigid limbs at right angles to each other, one limb constituting a lever terminating at its outer free end in an oblique foot, said foot being undulated to provide longitudinally spaced heel and toe portions cooperable with the eye portion of said screw, and a hand-grip swivelly mounted on the remaining limb, said foot being at approximate right angles to the longitudinal axis of said hand grip.

2. A hand tool expressly adapted for handy and expeditious use in inserting, screwing and unscrewing screw-eyes comprising a rigid one-piece crank unit embodying a pair of rigid linearly straight limbs at right angles to each other, one limb constituting a lever and having a free

end portion which is obliquely bent and longitudinally undulated to provide an oblique-angled foot, the undulations defining a heel, a toe, and an intervening longitudinally bowed arch, and said heel, toe and arch providing selectively usable crotch portions, the free end of the remaining limb having a shoulder, washers secured on said last-named limb at longitudinally spaced points, one of the washers abutting said shoulder, and a sleeve surrounding the limb between said washers and providing a swivelly mounted hand-grip, said foot being disposed at approximate right angles to the longitudinal axis of said hand-grip.
